(57) **CLAIM**

The ornamental design for a footwear care machine as shown and described.

DESCRIPTION

FIG. 1 is a front, top, and right perspective view of a footwear care machine showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front, top, and right perspective view showing the doors transitioned to an alternate “see through” state.

The broken lines depict portions of the footwear care machine that form no part of the claimed design.

1 Claim, 8 Drawing Sheets
